CLAIM

We claim the ornamental design for the chair, as shown and described.

DESCRIPTION

FIG. 1 is a perspective view of a chair embodying the present invention;

FIG. 2 is a front perspective view of the chair shown in FIG. 1;

FIG. 3 is a side elevational view of the chair shown in FIG. 1, the opposite side view being a mirror image thereof;

FIG. 4 is a rear perspective view of the chair shown in FIG. 1;

FIG. 5 is a top plan view of the chair shown in FIG. 1; and,

FIG. 6 is a bottom plan view of the chair shown in FIG. 1.
